ROBERT A. DUNNING, OF YARMOUTH, MAINE, ASSIGNOR TO KNULAND SHAFFER,
TRUSTEE, OF BOSTON, MASSACHUSETTS.

SPONGE THREAD.

1,002,829.

Specification of Letters Patent. Patented Sept. 12, 1911.

Application filed October 7, 1908. Serial No. 456,655.

To all whom it may concern:

Be it known that I, ROBERT A. DUNNING, a citizen of the United States, residing in Yarmouth, county of Cumberland, State of Maine, have invented certain new and useful Improvements in Sponge Thread, of which the following is a specification, reference being had to the drawings accompanying the same and forming a part 10 thereof.

This invention relates to a form of sponge thread consisting of small particles of sponge held together by a thread or threads.

The object of the invention is to utilize 15 sponge in the production of a thread which may be woven on any suitable loom with any preferred material for warp and woof in the production of fabrics for various uses, such as for bath towels, bath mats, wash 20 cloths, harness pads, and for other purposes too numerous to mention.

In the accompanying drawings forming a part of this specification and in which like characters indicate corresponding parts— 25 Figure 1 is a plan view of a sponge sheet composed of small particles of sponge held together by a suitable sizing of a mucilaginous nature, soluble in water or other fluids; Fig. 2 is an end sectional elevation taken 30 centrally through Fig. 1; Fig. 3 is a plan view of two sponge sheets as they appear, held together by stitching on a quilting machine which sews them on lines 1—2, etc.; and Fig. 4 is a side view of a sponge thread 35 composed of particles of sponge held together by thread passing through them.

In the manufacture of sponge thread, I take sponge, sort it and free it from shells or other foreign matter and impurities, then 40 run it through a picking machine to pick it to any required degree of fineness. This product is washed and dried and then treated with a suitable mucilaginous sizing which may be gelatin and paraffin compound, glue 45 and soap, or any other suitable sizing. The

particles of picked sponge are then spread out in thin sheets to make the proper thickness of sponge sheet for the intended use, and pressed to cause the pieces of sponge to adhere together. After the sizing has dried 50 and set, the sheets of sponge are then run through a quilting machine, as illustrated in Fig. 3, to produce rows of stitching a sufficient distance apart to make the threads of sponge of suitable size for the purpose in- 55 tended. The sheets are then cut between the rows of stitching. The sizing may then be washed out of the sponge thread so that the sponge will resume its normal absorbent condition, when it is ready to be woven into 60 the kinds of fabric that it is designed to produce.

As seen in Fig. 3, the stitching shows plainly, but when the sizing has been washed out, the sponge will swell, renewing its cel- 65 lular absorbent condition so that the stitching will be entirely concealed, and the par- ticles of sponge resume their moisture-ab- sorbent and retaining characteristics.

Having thus described the invention, what 70 I claim is—

1. A new article of manufacture, comprising a continuous rope or thread of sponge joined together by a thread or threads stitched through a plurality of particles of 75 sponge.

2. A new article of manufacture consisting of a thread or string of sponge, comprising a plurality of particles of sponge combined and held together by a plurality of 80 threads stitched through them.

In testimony whereof, I have hereunto set my hand, in the presence of two subscribing witnesses, this the fifteenth day of Sept. A. D. 1908.

ROBERT A. DUNNING. [L. S.]
